UNITED STATES PATENT OFFICE.

JOHN I. HOLDER, OF BURLINGAME, CALIFORNIA, ASSIGNOR TO THE PARAFFINE COMPANIES, INC., OF SAN FRANCISCO, CALIFORNIA, A CORPORATION OF DELAWARE.

FLASHING STRUCTURE.

Application filed March 10, 1925. Serial No. 14,381.

My invention relates to flashing structures and especially for use with prepared flexible roofing.

An object of my invention is to provide 5 a convenient support to which the edge of the roofing may be fastened.

A further object of my invention is to provide a waterproof seal for the roofing edge.

10 My invention possesses other objects and features of advantage, some of which, with the foregoing, will be set forth in the following description of the preferred form of my invention which is illustrated in the 15 drawings accompanying and forming part of the specification. It is to be understood that I do not limit myself to the showing made by the said drawings and description, as I may adopt variations of the preferred 20 form within the scope of my invention as set forth in the claims.

In the drawings, Figure 1 is a perspective view of a roof and supporting walls embodying my invention, portions of various 25 parts being broken away;

Fig. 2 is a cross section taken on lines 2—2 of Fig. 1.

Fig. 3 is a cross sectional view of the 30 grooved flashing strip.

Broadly speaking, my flashing structure 35 comprises a strip of any suitable material such as wood, and is adapted to be mounted on a suitable substructure usually comprising the parapet wall. Recesses are provided 40 in the strip for containing a plastic material which forms an impervious seat for the edge of a sealing piece or apron. The apron is held in position by suitable fastening means which are anchored in the strip, 45 and overlies the upturned edge of the roofing sheet which may be attached to the strip in any suitable manner, such as by nailing.

In the preferred form of my invention, I 45 provide a four-sided strip of wood 3, or other suitable material, and which has one of two opposite sides narrower than the other. This shape is especially adapted for use with concrete walls, and if the strip is so used it is nailed to the forms, with the 50 narrow side 4 next them, prior to the pouring of the concrete. When the forms are removed from the walls the strip remains imbedded or interlocked in the concrete with

its narrow side exposed. Preferably the strip is treated with a bituminous or other 55 suitable material to render it waterproof.

In the thus exposed face of the strip is a longitudinal groove 6 filled with plastic material 7 preferably of bituminous nature and water-proof. The narrow flange 8 of the apron 9 which is preferably made of about 20 gauge galvanized iron, is inserted into the plastic material and firmly held in position by hooked nails 11 driven into the groove. The plastic material not only helps to hold the apron in place, but also forms a tight seal about its embedded edge. The apron 9 overlies the edge of a flexible roofing material 12, which is attached to the wood strip by suitable nails 13. Ordinarily, 60 roofing of the type mentioned because of its flexibility cannot be laid vertically against the parapet wall for a height of more than a few inches, but my flashing structure provides a place to which it may be readily attached at any convenient height. This feature is shown in Fig. 1, in which the roofing sheet 12 is extended upwardly to the strip from the plane of the roof 14 and against the parapet wall 16.

After the driving of the hooked nails to secure the apron, the whole is preferably given a mop coating 17 of bituminous material, as a final sealing and protective coat.

Not only does my flashing structure permit the secure sealing of the edge of the roofing, but it lends itself readily to application in positions and at heights above the roof deck not possible with any other structure. Furthermore it is cheaply made and 85 readily installed and because of the ease of cutting the strip it is quickly fitted in corners and around pilasters and other irregular portions. The face of the wooden strip below the groove provides a convenient 90 nailing place to which the edge of the roofing may be securely attached by roofing nails and with the sealing of the apron a mechanically secure and tight structure results.

I claim:—

1. An article of manufacture comprising a flashing strip having a longitudinal groove therein, and a normally plastic material in said groove.

2. A flashing structure for a roofing com-

prising a wooden strip shaped to interlock with a sub-structure and having a face to which roofing may be secured, said strip being formed with a longitudinal groove in 5 said face, a normally plastic material in said groove, an apron seated in said plastic material and overlying the fastened edge of

the roofing, and wedge members inserted in said groove for fastening said apron in place.

In testimony whereof, I have hereunto set my hand.

JOHN I. HOLDER.
